UNITED STATES PATENT OFFICE.

LEMERT CHALKLEY VAN VOORHIS, OF SALT LAKE CITY, UTAH.

STATEMENT AND BALANCE BOOK.

992,618.

Specification of Letters Patent. Patented May 16, 1911.

Application filed February 9, 1909. Serial No. 476,926.

To all whom it may concern:

Be it known that I, LEMERT C. VAN VOORHIS, a citizen of the United States, and a resident of Salt Lake City, in the county of 5 Salt Lake and State of Utah, have invented certain new and useful Improvements in Statement and Balance Books, of which the following is a specification.

My invention is an improvement in loose 10 leaves and index sheets for loose leaf binders, and consists in certain novel constructions and combinations of parts, hereinafter described and claimed.

In the drawings—Figure 1 is a plan view 15 of the loose leaf, Fig. 2 is a perspective view of the index sheet, a portion of the covering being removed at one end, Fig. 3 is an edge view of a portion of the index sheet and a portion of the loose leaf, and Fig. 4 is a perspective view of a portion of the improvement. 20

The embodiment of the invention shown in the drawings consists of a plurality of loose leaves or sections A, and a plurality 25 of index sheets B, a loose leaf being superimposed on each index sheet. Each index sheet consists of two portions b and b² connected by a cover b¹¹ of flexible material, as for instance cloth, and one of said portions b consists of superimposed strips b⁰ and b^x 30 provided near each end with slotted perforations b', and spaced apart at their ends by a transverse strip b¹⁵, so that the portion is thicker at its ends than at its center. The other portion b² consists of a plurality of superimposed sheets b¹², b¹³ of stiff sheet material, and the sheets are separated at their 35 ends by transverse spacing strips b¹⁰, and the two portions are connected by the covering b¹¹ of fabric material, the arrangement being such that the portion b is spaced apart from the portion b², and flexibly connected thereto by the cover as at b⁸. The sheet b¹³ is also provided with the usual index tag b⁶.

The loose leaf comprises a plurality of statement sheets, a, which are superimposed upon each other in underlapping relation, one edge of the statements being connected 50 by a tape a', the tape and the statements being provided with slotted perforations a², which are adapted to register with the perforations b' of the portion b when the loose leaves are superimposed thereon. Each of the statement sheets consists of a central

portion a³ which is ruled and headed in the form of a statement, a balance coupon a⁵ ruled and headed to receive a balance, and a reconciliation coupon printed as shown at a⁶, the balance coupon being separated from the central portion by a line of perforations a¹⁶, and the statement proper being separated from the reconciliation coupon by a line of perforations a¹⁷, the said lines of perforation extending the full length of the sheet as shown in Fig. 1. By means of the above described lines of perforation, the balance coupon and the statement proper, that is portions a⁵ and a³ may be separated from the reconciliation coupon a⁶.

The sheets forming the loose leaf as before stated are arranged in superimposed and underlapping relation, the lowermost sheet being at the top of the loose leaf and the uppermost sheet being at the bottom. 70 Each of the sheets is provided at its top with the name of a depositor as shown at a⁷ and the sheets are so arranged that all names thereon are always visible as shown in Fig. 1. The numeral designating the ledger page upon which the account of the depositor whose name appears on the statement is found, follows the name as at a⁸, and since some of the pages of the ledger will bear more than one account the numerals a⁸ will be repeated. The statements are arranged before binding, with the names alphabetically and a colored blank sheet a⁹ is arranged between the sheets bearing series 75 of names commencing with one letter of the alphabet and the series commencing with another letter. 80

It will be observed that by arranging the sheets in superimposed underlapping relation, the loose leaf is thin at its ends and thick at its center, and since the index sheet is thin at its center and thick at its ends, each index sheet and its corresponding loose leaf when placed together will form a section having approximately parallel upper 85 and lower faces.

As shown in Fig. 1, the statements proper are ruled with a plurality of parallel horizontal lines a¹⁰ which are crossed at spaced intervals by vertical lines a¹¹, a series of vertical columns being thus formed. The first column is headed "Date," the next four are each headed "Checks," the sixth column is headed "Checks" and "Balance" the word "Balance" being arranged beneath the word 90 95 100 105 110

"Checks," the seventh column is headed above the ruling "Debit" and at the top of the column it is headed "Total checks." The eighth and ninth columns are headed 5 above the ruling "Credit," and at the top of the columns "Deposits." The tenth column is headed "Memo." The statement coupon shown to the right of the line of perforation ^{a¹⁶} in Fig. 1 is divided into three vertical columns, the first one of which is arranged beneath the heading "Memo." and bears a series of numerals arranged one above the other and running consecutively from above downward from 1 to 31, and the 10 second and third columns are headed "Balance."

Statements arranged in the manner shown, serve as a bank balance book or teller's record, from the first to the last of the month, 20 after which the statements are taken from the book and delivered to the customers with their canceled vouchers. The numbers or numerals on the statements under the column headed "Date" designate the days of 25 the month, and the colored sheets which divide the various series of names on the loose leaf are for assistance to the teller or other officers in referring to the various accounts.

It will be understood that the loose leaves 30 and the index sheets are intended to be bound in book form in a loose binder, and each loose leaf and its index sheet forms a book section having substantially parallel faces, the thick ends of the index sheet compensating for the thin ends of the loose leaf.

I claim:

1. A book of the class described composed of a plurality of loose leaves or sections, each leaf comprising a plurality of sheets superimposed in underlapping relation, whereby 40 to expose a portion of the top of each sheet, said portion bearing a name and a number, the sheets being arranged in series, each series comprising the names commencing with one letter of the alphabet, and a sheet of a contrasting color between the series, said first 45 named sheets being each partially divided into three portions, the central portion being headed for a statement, the outer portion being headed for a balance sheet, and the 50 inner portion bearing a printed notice, each of said sheets being provided with a score

line near its bound edge for the purpose set forth.

2. A book of the class described, composed 55 of a plurality of loose leaves or sections, each leaf comprising a plurality of sheets, superimposed in underlapping relation, whereby to expose a portion of the top of each sheet, said portion bearing a name and 60 a number, the sheets being arranged in series, each series comprising the names commencing with one letter of the alphabet, and a sheet of a contrasting color between the series, each of said before named sheets being 65 provided with a score line near its bound edge for the purpose set forth.

3. A book of the class described, composed of a plurality of loose leaves or sections, each leaf comprising a plurality of sheets of 70 equal size and superimposed in underlapping relation whereby to expose a portion of the top of each sheet, said portion being provided with a name and number, the sheets being arranged in series, each series comprising the names commencing with 75 the same letter of the alphabet and a sheet of contrasting color between the series, each of said named sheets being provided with a score line at its inner bound edge for the purpose 80 set forth.

4. A book of the class described, composed of a plurality of loose leaves or sections, each leaf comprising a plurality of sheets superimposed in underlapping relation, 85 whereby to expose a portion of the top of each sheet, said portion bearing a name and number, the sheets being arranged in series, each series comprising the names commencing with the same character, and a sheet of 90 a contrasting color between the series.

5. An index sheet comprising superimposed sheets, a strip arranged between the sheets at each end thereof, the centers of the 95 said sheets being in contact, strips provided with slotted perforations whereby they may be bound spaced apart from one side of the sheets, and a flexible cover for the sheets and the strips and connecting the sheets with the said strips.
